UNITED STATES PATENT OFFICE.

ROBERT MORSE WITHYCOMBE, OF SYDNEY, NEW SOUTH WALES, AUSTRALIA.

NAILBRUSH.

Application filed March 31, 1925, Serial No. 19,709. Renewed April 7, 1927.

This invention relates to brushes and particularly to brushes of the type having a core which is removable from the back or handle portion.

5 The object of the invention is to construct a brush having a recessed back and an elastic core, a transverse dimension of the latter being slightly greater than the corresponding dimension of the recess, said core being bendable archwise for insertion into said recess, and expanding through its inherent elasticity into contact with the walls of said recess, being in this manner retained in place, the relative size of the recess and core being 15 such that the condition of stress in said core produced by arching it, is not entirely relieved by its expansion into the recess, so that pressure upon the face of the brush incident to its use, tends further to flatten the 20 arched core, augmenting the side thrust of the core against the walls of the recess and the more securely retaining the core in place.

Other objects of the invention will appear as the following description of illustrative 25 forms of the invention proceed.

In the drawings:—

Figure 1 is a side elevation partly in section showing a form of my invention.

30 Figure 2 is a section taken along the line 2—2 of Figure 1.

Figure 3 is a section taken along the line 3—3 of Figure 1.

Figure 4 is a detail view partly in section showing a slightly modified form of the invention.

Figure 5 is a detail view in section showing still another form of the invention.

Referring now in detail to the several figures, the numeral 1 represents the back or handle part of the brush and 2 the core which carries the bristles or filaments. In that form of the invention illustrated in Figure 1 the core is formed of a strip of rubber cut transversely along one edge into filaments 3, and rolled together, and vulcanized. The back or handle 1 is formed with a recess 4 into which the core is adapted to be inserted. Said core is made slightly larger in one of its transverse dimensions than the corresponding dimension of the recess so that in order to effect the insertion of said core into said recess it is necessary to bend the core into an arch shape as shown at 5 in Figure 1, placing it under stress. When the core is inserted into the recess as shown, it expands, tending to re-

assume its condition of repose but is restrained by the side wall 6 of the recess against which wall it presses with a force sufficient to retain the core securely within 60 said recess. By this construction, pressure upon the face of the brush is transmitted as lateral stress against the side wall of the recess further augmenting the pressure between said core and the back of the brush 65 and retaining the parts the more securely together.

In that form of the invention shown in Figure 1 the recess has a cylindrical wall, this form of recess being easy to mold and 70 the pressure between the core and said side wall being adequate in ordinary circumstances for the retention of the core. There may be instances, however, where an extraordinarily secure attachment is desired, in 75 which cases it may be preferable to mold or otherwise form the recess with an undercut side wall as indicated at 7 in Figure 4.

While I prefer to form my improved brush with a core of laminated strip rubber 80 having integral filaments, as above described the invention is by no means limited to such construction, but may be exemplified in numerous other forms and arrangements of structure. For instance, in Figure 5 I have 85 illustrated the core as being made of an elastic rubber block 8 in which ordinary bristles of animal origin are embedded.

The invention lends itself readily to the 90 construction of a brush in which the handle or back is of such ornamental or intrinsic value that it may be desired from time to time to replace the core without discarding the entire brush. For sanitary purposes, 95 also, it is advantageous to have a brush, the inserted or filamentous portion of which may be removed for boiling in water, or other process of sterilization. It is an easy matter to grasp the core by the middle and to remove it from the handle, the core bending through its inherent elasticity and permitting easy withdrawal. The new core is inserted by pressing it at diametrically opposite points until it has arched convexly 100 in the direction of its face to a sufficient degree to permit its insertion within the recess of the handle.

Having described my invention what I 110 claim as new and desire to secure by Letters Patent, is:—

A brush including a back formed with a recess, and a core having a filamentous face,

said core being elastic and normally having a lateral dimension slightly exceeding the corresponding dimension of said recess, said core being compressed to arch the same outwardly and being seated in said recess, the depth of the recess and the thickness of the core therewithin, exceeding the height of the crown of the arched inner face of the

core, whereby the stress induced by the arching of the core is transmitted through the core to the walls of said recess in opposite directions, in lines of force which lie substantially in the same or parallel planes. 10

In testimony whereof I have hereunto set my hand.

ROBERT MORSE WITHYCOMBE.
